C. G. DAVIS

APPARATUS FOR WASHING ICE CREAM CANS

Filed June 22, 1926

Inventor

C. G. Davis

By

Lacy & Lacy. Attorney

UNITED STATES PATENT OFFICE.

CLEVELAND G. DAVIS, OF GRAND RAPIDS, MICHIGAN.

APPARATUS FOR WASHING ICE-CREAM CANS.

Application filed June 22, 1926. Serial No. 117,815.

The present invention relates to can washing apparatus and more particularly to apparatus for cleaning cans in which ice cream, ices and other frozen delicacies are marketed.

- 5 The invention consists of a tub or like receptacle, a splash board at the back and ends thereof, a rack suspended within the upper portion of the tub to receive the cans, a pipe for supplying hot water, steam or 10 other medium, a distributing pipe within the tub and extending below the rack, and valved nozzles for delivering the cleansing medium in jets against the inner walls of the cans to thoroughly cleanse the same.
- 15 While the drawings illustrate a preferred embodiment of the invention, it is to be understood that in adapting the means to meet specific needs and requirements, the design may be varied and such other changes 20 in the minor details of construction may be resorted to within the scope of the invention as claimed, without departing from the spirit thereof.

For a full understanding of the invention 25 and the merits thereof, reference is to be had to the following description and the drawings hereto attached, in which,—

Figure 1 is a perspective view of apparatus embodying the invention, particularly 30 designed for washing or cleaning ice cream cans, the dotted lines showing one of the cans in position, and

Figure 2 is a vertical transverse sectional view thereof.

35 Corresponding and like parts are referred to in the following description and designated in both views of the drawings by like reference characters.

The stand, or supporting structure includes a rectangular frame 1 and legs 2, the latter being preferably of L-form so as to embrace the corners of the tub or receptacle 3 which is provided at the top of its sides or walls with an outer flange 4 to overhang 40 and rest upon the frame 1. The bottom of the tub or receptacle 3 is of synclinal form and a valve 5 is provided at one end at the lowest point to draw off the contents when it is required to drain the tub. A 45 splash-board 6 is provided at the back and partly along the ends of the tub adjacent the back and a top 7 projects forwardly from the back of the splash-board 6 and connects with the portions at the ends of the tub. 50

55 The top 7 prevents jets of steam or water from being thrown to a height to splash

the ceiling, walls or floor of a room or other place in which the apparatus may be located. The back and end portions of the splash-board rise from the outer edge of the over-hanging portion 4 of the tub. 60

A rack 8 is suspended within the upper rear portion of the tub 3 and comprises spaced longitudinal bars having opposite end portions bent vertically to extend along 65 the ends of the tub, thence laterally to overhang and rest upon the tub, whereby to support the rack. The cans to be washed are inverted upon the rack 8 and jets of water, steam or other medium, are delivered within 70 the cans against the bottom and sides thereof in a manner to remove all matter and thoroughly cleanse the interior of the cans, which are thus sterilized and caused to dry 75 without the necessity of wiping the interior of the cans.

The numeral 9 designates a supply pipe which connects with a source of steam, water or other cleansing medium and this pipe extends through the back portion of the splash board 6 and depends to a point adjacent the back of the tub and below the rack 8 where it makes connection with a longitudinally disposed distributing pipe 10 to which valved nozzles 11 are connected, said nozzles projecting slightly above the rack 8 and having openings in the top and sides for delivering jets of hot water, steam or the like, against the bottom and inner sides of the cans placed upon the rack 8. The valved nozzles 11 admit of any one or more of the nozzles being cut-off when it is desired to wash only one or a number of cans less than the number of nozzles, thereby preventing the waste of 90 hot water or steam in the use of the apparatus. The supply pipe 9 is provided in its length with a valve 12 which admits of controlling the flow of the cleansing medium, such as hot water or steam, to the 95 distributing pipe 10 from which the flow is controlled by the valves of the respective nozzles 11. The tub 3 collects the water and the matter removed from the cans during the washing operation and when it is required to draw off the contents of the tub 3 the valve 5 is opened. While the apparatus is particularly designed for washing the cans in which ice creams, frozen custards, water ices, and the like are packed, 100 nevertheless, it is to be understood that the apparatus may be advantageously used for 105 110

washing milk cans and analogous containers.

Having thus described the invention, I claim:

- 5 1. Can washing apparatus comprising a tub, a rack suspended within the upper rear portion of the tub, a splash board at the back and ends of the tub adjacent the back, and including a top extending forwardly from the back and connecting it with the end portion, a supply pipe and a distributing pipe connected with the supply pipe and extending beneath the rack and provided at intervals in its length with 10 valved nozzles.
2. Can washing apparatus comprising a supporting frame, including legs, a tub having an outer flange at its top to extend over and rest upon the said frame, a rack suspended within the rear portion of the top and having opposite end portions extending vertically, thence outwardly to overlap and rest upon the tub, a supply pipe and a distributing pipe connected with the supply pipe and extending beneath the rack and provided at intervals in its length with 15 valved nozzles.

In testimony whereof I affix my signature.

CLEVELAND G. DAVIS. [L. S.]
